HOLE SHEAR OR THE LIKE FOR REPAIRING
SEWN-IN BICYCLE TUBE TIRES

Philip Joseph Quartararo, 2309 Ave. Y, Brooklyn, N.Y.

Filed Aug. 21, 1964, Ser. No. 81,389

Term of patent 3½ years

(Cl. D54—13)

$\frac{1}{2}$

FIG. 1

$\frac{1}{2}$

FIG. 3

FIG. 4

FIG. 5

FIG. 6

FIG. 1 is a front elevational view of a hole shear or the like for repairing sewn-in bicycle tube tires embodying my new design, the rear elevational view being identical thereto;

FIG. 2 is a top plan view thereof, looking along line 2—2 in FIG. 1;

FIG. 3 is a side elevational view thereof, the opposite side being identical thereto;

FIG. 4 is a sectional view thereof, taken along the line 4—4 in FIG. 3;

FIG. 5 is a sectional view thereof, taken along the line 5—5 in FIG. 3; and

FIG. 6 is a bottom plan view thereof, looking along line 6—6 in FIG. 3.

I claim:

The ornamental design for a hole shear or the like for repairing sewn-in bicycle tube tires, as shown.
